Application November 21, 1938, Serial No. 241,519

15 Claims. (Cl. 153—10)

This invention relates to an apparatus for treating pistons, and is a continuation in part of my prior application for Method of treating pistons, Serial No. 159,313, filed August 16, 1937, now Patent No. 2,149,787. The invention relates to piston expanding and is concerned with a novel machine for expanding the skirts of worn pistons after service in engines to enlarge the piston skirt to better fit the cylinder in which it is installed. With my invention a machine is provided wherein a piston may be fixed in position in the machine, and upon operation of the machine the piston will be acted against at its inner sides and at diametrically opposite 15 points by impact rods, the force of the impact serving to displace the metal and stretch the piston skirt around its outer peripheral surface to thereby enlarge the skirt and cause it to more closely fit a cylinder in which it is used. With 20 the machine the piston may be turned about its vertical axis while the operation is being performed, to thereby effect a substantially uniform or more nearly uniform treatment of the skirt entirely around it; and further, means are provided for moving the piston vertically with respect to the impacting members whereby a wider vertical zone of impact around the inner side of the skirt is had, with a resultant better operation.

It is an object and purpose of the present invention to provide a machine for the purpose stated, and also for the attainment of many other beneficial results which will be hereinafter described. As one desirable feature in connection with the machine, a means is provided for setting the machine for a predetermined impacting operation upon a piston, the machine operating and performing its work for a preselected period of operation, and after the desired period has elapsed and the desired treatment of the piston has occurred, the machine will be automatically stopped in operation.

An understanding of the invention may be had from the following description, taken in connection with the accompanying drawings, in which:

Fig. 1 is a front elevation of the machine made in accordance with my invention, with some parts broken away for a better disclosure of the machine.

Fig. 2 is a vertical section and side elevation of the machine, the section being approximately on the plane of line 2—2 of Fig. 1.

Fig. 3 is a partial horizontal section and plan, a part of the section being taken on the plane of the upper horizontal line 3—3 and another 55 part on the plane of the lower line 3—3 in Fig. 1.

Fig. 4 is a horizontal section upon the plane of line 4—4 of Fig. 1.

Fig. 5 is a vertical section substantially on the plane of line 5—5 of Fig. 1.

Fig. 6 is an elevation partly in section, looking 5 at Fig. 5 from the left.

Fig. 7 is a fragmentary transverse vertical section on the plane of line 7—7 of Fig. 2.

Fig. 8 is a fragmentary vertical section substantially on the plane of line 8—8 of Fig. 5, and 10

Fig. 9 is a vertical section and plan substantially on the plane of line 9—9 of Fig. 2.

Like reference characters refer to like parts in the different figures of the drawings.

The supporting structure for the machine includes a base member 1 and a hollow housing 2 thereover, secured in place and which toward the front end at one side has an upwardly extending hollow extension 3. In front of said extension the housing includes a horizontal ledge 4 in 15 which a slot 5 is made as shown.

From the base, supporting feet or lugs 6 extend (Fig. 2) upon which are carried members 7 bolted thereto, between which a tubular housing 8 extends, at its ends being carried by said members 7 in any suitable manner. A shaft 9 extends through the tubular housing 8 and between its ends has a spirally threaded or worm section 10 (Fig. 2). The shaft extends at both ends beyond the tubular housing 8 and at its rear end is equipped with a wheel 11 driven through an endless belt 12 by an electric motor 13. At the front end of the shaft 9 a disk 14 is mounted, from which a pin 15 projects in a forward direction, on which a roller 16 is mounted. The pin 15 is set a distance from the center of the disk, as shown in Figs. 1 and 2.

A vertical bar 17 passes through the slot 5 and lies in front of the upward extension 3 of the housing. At the lower end the bar is vertically slotted so that the pin 15 and the roller 16 may extend between the vertical portions of the bar at opposite sides of the slot. Also spaced vertical guides 18 of angle bar are riveted or otherwise permanently connected to the front face of the bar 17 against the inner flanges of which the roller 16 bears. The bar 17 toward its upper end is carried by a horizontal stub shaft 19 which extends through and is rockingly mounted near the upper end of the extension 3 of the housing. 40 With this construction when the motor 13 is receiving and drives the shaft 9, the bar 17 is oscillated rapidly back and forth about the axis of the shaft 19, the length of the slot 5 being such as to permit such oscillation.

45

50

55

A short distance above the ledge 4 of the housing 2 a supporting shelf 20 is permanently secured to and extends in front of the bar 17. Shelf 20 is in a horizontal position, and as shown in Fig. 4, has opposed extensions in each of which a slot 22 is cut. Piston locating members 23 with vertical flanges 24 of substantially V-form are adjustably mounted on the sleeve 20 and may be retained in any position to which 10 moved by tightening the bolts 22a which pass through the slots 22 and through said members 23. The piston 21 which is to be treated is located with the skirt portion thereof extending downwardly and with the lower end of the piston resting upon the shelf, the skirt being between the upwardly extending flanges 24, which are adjusted toward the piston to locate it approximately or as close as possible centrally with respect to the center of the table 20. But the 15 locating members 22 are not brought into clamping engagement with the outer sides of the piston skirt, but bear lightly against said piston skirt whereby the piston may be moved up and down readily without being held by any clamping engagement thereagainst.

Above and at the central portion of the shelf 20 a rod holding block 25 is located and permanently secured, whereby when the piston is placed upon the shelf the skirt portion is located over 30 the block which extends upwardly into the piston a considerable distance, as shown in Fig. 1. The rod holding block has a plurality of horizontal passages therethrough at closely spaced vertical distances from each other in which the impacting rods 26 are loosely mounted. Preferably, though not necessarily, the ends of the rods 26 are pointed, but the shape and formation of the ends of the rods are subject to wide variation.

40 At the front face of the bar 17 a vertical guide 27 is secured extending from the upper end of bar 17 downwardly toward the table 20 as shown in Fig. 2. Such guide as shown in Fig. 9 has inwardly tapered side edges. A supporting bracket and housing 28 is located in front of the guide 27, having rearwardly extending lower and upper horizontal arms 29 and 30, shaped at their rear ends to engage with the inwardly tapered edges of the guide bar 27, and 45 the lower arm 29 is split and equipped with a clamping arrangement operated by a handle 31 whereby the bracket 28 may be raised or lowered for adjustment to different positions on the guide bar 27 and clamped in any position to 50 which is adjusted.

55 A vertical rod 32 extends through the front portion of the bracket housing 28, being equipped at its upper end with a handle 33 pivotally connected thereto which is forked at its inner end (Fig. 9), the free ends of the forks having rounded surfaces 34, as shown. The handle may be manually operated to turn the rod 32 about its vertical axis, or by turning the handle 31 upwardly, the rounded ends 34 engaging against 60 the upper side of the bracket housing 28 will move the rod in a vertical direction against a compression spring 35 which is housed within the bracket 28.

70 Rod 35 at its lower end has a collar 36 fixed thereto from which an arm 37 extends rearwardly and is curved downwardly, at the lower end of which is a second collar from which a horizontal pin 38 extends in a forward direction. A bracket 39 is pivotally mounted between its 75 ends on the pin 38 and extends laterally in both

directions therefrom. At its central under portion two spaced apart lugs extend downwardly, (Fig. 1) through which a rod 40 passes, the central portion of the rod being plain or unthreaded for free rotation in said lugs but outwardly therefrom being oppositely threaded, one portion threaded with right hand threads and the other with left hand threads. A collar 41 is fixed to the rod 40 and located between the lugs depending from the bracket 39. Two clamping shoes 42 are mounted on the rod 40 underneath the bracket 39, one on each of the oppositely threaded sections of the rod, whereby on rotating the rod by engaging the thumb nut at one end thereof the clamping shoes may be simultaneously separated or moved toward each other, depending upon the direction that the rod is turned. The clamping shoes having depending clamping flanges, are adapted to be brought against opposite sides of the upper end of the piston 21 which is to be treated and clamped tightly against the piston, whereby upon manual operation of the handle 33 to rotate the rod 32, the piston is turned about its vertical axis, and upon turning the handle 31 upwardly, the piston is elevated, the non-clamping position of the locating members 22 permitting such vertical movement of the piston.

With this construction, in operation, shaft 9 being rotated by the motor, the bar 17 is rapidly moved back and forth at its lower end rocking on the shaft 19. The table 20 being connected to the bar 17 is likewise moved back and forth in a horizontal plane, the piston 21 and the block 25 moving with it. Such rapid movement 35 causes the impacting rods 26 to be rapidly reciprocated in the guide passages therefor through the block 25 and the ends of the rods are impacted against diametrically opposed inner points of the piston. The handle 33 may be used to 40 turn the piston about its vertical axis and thus cause the impingement of the ends of the rods 26 over the entire inner portion of the piston skirt. The handle also, by moving the same upwardly, may change the position of the piston 45 vertically with respect to the impacting rods and thus affect a wider area of treatment of the skirt. The impact and impingement of the ends of the rods 26 against the opposite inner sides of the piston skirt is substantially equal at both 50 ends of the rods with a resultant symmetrical enlargement of the piston skirt. The piston, usually of aluminum or aluminum alloy, has the inner surface portions of the skirt indented by the pointed rods or peaned with rods having 55 other formation at their ends, causing an increase of the circumference of the piston skirt, which increase or enlargement may be only a few thousandths of an inch, but sufficient to compensate for the wear which has taken place and 60 substantially restore the piston to a size to correspond with the cylinder in which it is operated in those cases where wear upon both the cylinder and the piston has made the fitting of the piston within the cylinder too loose.

65 All pistons do not require the same degree of treatment, some requiring a greater expansion than others in accordance with the slack or looseness of fit which is to be remedied. With this invention I have provided means whereby a 70 preselected degree or extent of the impacting treatment of the rods against the inner side of the piston skirt may be used and when such treatment has ended, the machine automatically stops through breaking the electric circuit 75

through which current is supplied to the motor 13.

At one side of the upper extension 3 of the housing 2 a second vertical hollow housing 43 is located and secured over an opening in the upper side of the housing 2. At the front side of the housing 43 a dial 44, circular in outline, is secured, over which a setting hand 45 is adapted to move, the hand being fixed at the front end 10 of a shaft 46 which extends rearwardly into and through the housing 43. The hand in one direction of movement comes against a stop head 47 at which position it points to zero on the indicating dial. A friction clutch 48 connects a 15 worm wheel 50 with shaft 46, the worm wheel being driven by a worm 51 loosely mounted on a vertical stub shaft 52 (Fig. 6) and which has a detachable clutch connection at its lower end with a driving head 53 which in turn is driven 20 by a flexible shaft 54, housed within an outer protective armor tube 55. The shaft 54 and its covering 55 extend downwardly toward the shaft 9 and through a worm wheel 56 at the lower end of the shaft 54 and which is in meshing engagement 25 with the worm 10 on the shaft 9, said flexible shaft 54 is driven at a relatively low speed. As shown in Fig. 6, the outer sleeve or armor 55 around the flexible shaft is held in position by a releasable clamp consisting of the members 58, 30 but on releasing said members 58 the flexible shaft and the driving head 53 may be pulled downwardly and disconnected from the worm 51, if at any time it is necessary for repair or replacement or any other attention to the flexible shaft. 35

At the outer and rear end of the shaft 48 a dog 59 (Figs. 5 and 6) is secured, adapted when the indicating hand points to zero, to engage with a weighted dog lever 60 which has a weighted end 60a and which is secured to the stub shaft 61 below the shaft 48 and, like it, extending inwardly through the rear side of the housing 43. At its inner end, shaft 61 is securely connected to a clamping block member 62 which serves to releasably carry and hold a mercury switch element 63, having contacts in one end from which the circuit wires 64 lead. When the mercury switch 63 is in a horizontal position, as shown in dotted lines in Fig. 6, the mercury within the tube does not bridge between the contacts, one of which is over the other, and current cannot pass through the circuit. But when the mercury switch is tilted so as to lower the end thereof in which the contacts are located and 55 elevate the opposite end, the space between the contacts is bridged by the mercury and the circuit completed. With the switch in a horizontal position, when it is free to move, the weighted end 60a of the weighted lever 60 will tilt the switch 60 to close the circuit, but normally such movement is prevented by the friction engagement of a flat vertical bar or blade 65 (Fig. 5) which bears against the mercury switch to one side of the clamping block member 62 (Fig. 8), thereby holding 65 the switch in its inoperative position. The bar 65 is connected to a push rod 66 having a push button or head 67 at its forward end where it projects through and beyond at the front side of the housing 43, and is held in such projected position by the compression spring 68, as shown 70 in Fig. 4.

When a piston is to be treated with the machine and in accordance with the method of my invention, it is first measured to ascertain the extent of piston skirt enlargement required, then

placed in the machine and the setting hand 45 is turned away from the zero position and away from the stop 47 to a preselected position whereby said selecting hand will point to a preselected indicating figure on the dial 44. By experiment 5 and research the degree of enlargement which will occur for different periods of treatment has been ascertained. For a well worn piston which requires a considerably greater treatment than one less worn, the setting hand 45 will be moved 10 correspondingly farther away from its zero pointing position. For example, it might be turned to point to the figure 4 on the dial. But for pistons which have been less worn, the setting hand 45 will be turned a less distance. In any 15 case, when the hand 45 has been turned away from its zero pointing position, it is evident that the dog 59 will be moved counterclockwise (Fig. 6) away from its engagement with the weighted dog lever 60. Then by pressing upon the head 20 67 the mercury switch 63 will be freed for movement through moving the member 65 away from the switch, whereupon the switch will be tilted by the lever 60, with a resultant closing of the circuit to the motor 13. 25

As the treatment proceeds and the machine is driven by the motor 13, the hand 45 moves back from the position to which it has been set to its initial zero pointing position. The dog 59 moving with it approaches the upturned end of the 30 weighted lever 60, eventually striking thereagainst and automatically turning said lever 60 clockwise (Fig. 6) with a simultaneous turning of the mercury switch from its tilted circuit closing position to its horizontal circuit opening 35 position. Thus, when the machine has operated for a sufficient period such that the hand 45 has returned to its initial zero pointing position, the motor is then automatically stopped through the automatic breaking of the circuit which supplies 40 it with electric current, as described.

The machine described is one which has been improved and perfected over that shown in my prior application for patent to which reference has been made, and with it the desired operations are easily performed, producing a substantially perfect product. Many variations in constructive detail may be resorted to. For example, the impact rods 26, as previously stated, do not necessarily need to have pointed ends, and they 50 may be mounted in many different ways upon a holding guide block, not all of them necessarily being located one over the other, as shown in the present disclosure. An increase in the circumference or the stretching of the piston skirt in a 55 worn piston has come to be an accepted way of reconditioning pistons for further use. The method which I have invented, disclosed in my prior filed application, and the machine by which 60 such method is carried out as disclosed in the present application, produce the required enlarged piston skirt result in a rapid, practical and efficient manner.

The invention is defined in the appended claims 65 and is to be considered comprehensive of all forms of structure coming within their scope.

I claim:

1. In a machine of the class described, means for supporting a piston, means for oscillating said 70 supporting means back and forth in a direction substantially parallel to a diameter of the piston, and loosely mounted and guided impact members carried on said support within the piston and adapted to be longitudinally reciprocated when 75

- the piston is oscillated back and forth to strike against the inner side of the piston.
2. In a device of the class described, a support, a bar pivotally mounted at one end thereon, means operatively connected with the opposite end of the bar for oscillating said bar about its pivotal mounting, a support connected with said bar upon which a piston is adapted to be placed, means for holding the piston on the support whereby the piston is moved back and forth in a direction substantially parallel to a diameter of the piston, means for striking the inner surface of the piston carried by said table within the piston comprising a guiding block having guide openings therein substantially parallel to said diameter of the piston, and rods slidably received in said openings, the length of said rods being less than the diameter of the piston, as and for the purposes specified.
20. 3. A construction containing the elements in combination defined in claim 2, combined with manually operable means connected with the piston for turning the piston about its longitudinal central axis to present different portions of the inner sides of the piston to the ends of said rods.
4. In a machine of the class described, a vertical support, a bar pivotally mounted at its upper end on said support and extending downwardly, means connected with the lower end portion of the bar for oscillating said bar back and forth about its pivotal mounting, a horizontal support connected to and extending from said bar adapted to have a piston located thereon with the lower end of the piston resting upon said support, means for holding the piston in relation to said table whereby it oscillates therewith in a direction substantially parallel to a diameter of said piston, a block carried by said support within the piston having longitudinal substantially horizontal guide passages, and rods mounted for free movement in the passages in said block, said rods having hardened ends and the length of said rods being less than the inner diameter of the piston, as and for the purposes specified.
5. A construction containing the elements in combination defined in claim 4, combined with a vertical rod extending above the piston, means for mounting said rod on said bar whereby the rod may be turned about its vertical axis and means at the lower end of the rod adapted to have detachable connection with the piston whereby the piston may be turned about its longitudinal vertical axis on turning said rod.
55. 6. In a machine of the class described, a horizontal supporting table adapted to support a piston thereon with the open end of the piston resting upon the table, means for rapidly moving the table back and forth in a substantially horizontal plane in a direction parallel to a diameter of the piston, means for holding the piston against displacement with respect to said table, a member attached to said support located within the piston and extending upwardly within the piston, said member having horizontal guide passages, and rods loosely mounted in said guide passages in said member, the horizontal length of said member and the length of said rods being less than the internal diameter of the piston.
70. 7. A machine comprising a vertical support, a vertical bar suspended at its upper end from said support to rock about a horizontal axis, said bar being vertically slotted at its lower end portion, a horizontal shaft mounted for rotation on said support, a disk secured to one end of the shaft, a pin connected to the disk at a distance from the center thereof adapted to enter the slotted portion of said bar, a horizontal support secured to and extending from said bar, a block having a plurality of horizontal guide openings secured to and extending from said bar, a block having a plurality of rods mounted for free movement in said passages.
8. In a machine of the class described, means for supporting a piston, means for oscillating said supporting means and piston thereon back and forth in a direction substantially parallel to a diameter of the piston, impact members movably mounted in guides carried on said support within the piston, said members being longitudinally reciprocated when said support and piston is oscillated back and forth to thereby strike against the inner side of the piston, and means for turning the piston about its longitudinal axis as it is being oscillated.
9. In a machine of the class described, means for supporting a piston with its open end against the supporting means, means for oscillating said supporting means and the piston thereon back and forth in a direction substantially parallel to a diameter of the piston, and movably mounted impact members carried by said support within the piston adapted to move back and forth when the piston is oscillated, to thereby strike against the inner sides of the piston.
10. In a machine of the class described, means for supporting a piston, means for oscillating said supporting means and the piston thereon back and forth in a direction substantially parallel to a diameter of the piston, movable impact members within said piston carried by the supporting means adapted to be moved back and forth when the piston is oscillated to strike against the inner sides of the piston, and means for moving the piston in the direction of its central longitudinal axis while it is being oscillated.
11. In a machine of the class described, a support, a member pivotally suspended thereon, means for oscillating said suspended member back and forth, means for carrying a piston on said suspended oscillating member, impact members within the piston carried by said support movably mounted and adapted to impact against the inner sides of the piston upon oscillation of said suspended member, means for setting the machine while at rest for a predetermined period of impact treatment upon the piston, and means for automatically stopping said suspended member from oscillatory movement at the end of such period.
12. In a machine of the class described, a vertical support, a bar suspended adjacent its upper end for oscillating movement, a horizontal shaft, means for driving the shaft, operative connections between the shaft and the lower portion of said bar for rapidly oscillating said bar about its pivotal mounting on rotation of the shaft, a horizontal support connected with the bar adapted to have a piston positioned vertically thereon, means carried by said support within the piston including movable impact members which are moved back and forth upon the oscillation of the bar to strike against the inner sides of the piston, means for setting the machine while at rest for a predetermined period of impact treatment upon the piston, manual means for starting the mechanism in motion, and means for automatically stopping the machine at the end of said pre-selected period.

13. In a machine of the class described, a vertical support, a vertical bar pivotally suspended at one side of the support, a horizontal shaft rotatably mounted on said support, means to drive the shaft, connections between the shaft and said bar for rapidly oscillating the bar about its axis of pivotal suspension upon rotation of the shaft, a horizontal shelf connected to said bar above the shaft, said shelf being adapted to have a piston 5 located thereon with its open end against said shelf, movable impact members carried by said shelf within the piston adapted to move back and forth on oscillation of said bar, a rod mounted on said bar adjacent the upper end thereof and extending downwardly in front of the bar substantially over the upper end of the piston, clamping means carried by said bar for engaging opposite sides of the upper end portion of the piston, and

means for manually operating said clamping means to clamp against the piston or to be moved away therefrom to release said piston.

14. A construction as defined in claim 13, combined with means for mounting said rod for turning movement about its vertical axis and for longitudinal vertical movement, and a single means for turning the rod about its vertical axis and for moving it longitudinally upward.

15. A construction containing the elements in combination defined in claim 13, combined with means for mounting said rod on said bar and means for adjustably mounting said last mentioned means upon said bar for vertical adjustment thereupon and for securing it in any position to which adjusted.

HOLLY M. OLSON.
